PORTABLE MERCHANDISE DISPLAY STAND

Joseph Clement, Atlanta, Ga., assignor to Modern Metal Products Company, Greensboro, N.C., a corporation of North Carolina

Filed Oct. 21, 1966, Ser. No. 4,369

Term of patent 14 years

(Cl. D80—9)

FIG. 1

FIG. 3

FIG. 1 is a front perspective view of a portable merchandise display stand embodying my new design;

FIG. 2 is a front elevational view thereof; and

FIG. 3 is an end elevational view taken from one end thereof.

I claim:

The ornamental design for a portable merchandise display stand, as shown.
